UNITED STATES PATENT OFFICE

2,473,262

WIDE BAND HIGH-FREQUENCY
TRANSMISSION LINEMarvel W. Scheldorf, Schenectady, N. Y., assignor
to General Electric Company, a corporation of
New York

Application November 1, 1945, Serial No. 626,137

4 Claims. (Cl. 178—44)

1

My invention relates to a high frequency transmission line and it has for its primary object to provide a new and improved transmission line structure for conveying high frequency waves covering a relatively wide range of frequencies.

It is another object of my invention to provide a new and improved high frequency transmission line which may be easily adjusted for reflectionless transmission of waves thereover.

It is still another object of my invention to provide a new and improved high frequency transmission line which is simple to construct, in which the energy loss is reduced and in which the corresponding cost due to insulating material is reduced.

It is known, in the construction of transmission lines for conveying high frequency waves covering a relatively wide range of frequencies, that the coaxial type of line is desirable. Such a line necessarily employs insulators for maintaining the inner and outer conductors in spaced relation. Furthermore, for wide band transmission the number of insulators employed is often greater than that required for mechanical considerations. That is, each insulator introduces a reflection of high frequency energy and closely spaced insulators are required to reduce the net reflection of energy measured at the input terminals. Thus, heretofore, satisfactory transmission has been obtained by a transmission line in which insulators are regularly spaced, the spacing between insulators being determined by the length of the shortest wave to be transmitted.

It is an object of my invention to provide a new and improved high frequency transmission line of the coaxial type in which the number of insulators employed is minimized so that only insulators required for mechanical considerations are employed.

The foregoing objects are accomplished in one embodiment of my improved transmission line by employing intermediate the insulators required for mechanical considerations, a plurality of reflection members so spaced with respect to each other and with respect to the insulator of the line that sufficiently reflectionless transmission of energy over the line is effected.

The features of my invention which I believe to be novel are set forth with particularity in the appended claims. My invention itself, however, both as to its organization and method of operation, together with further objects and advantages thereof, may best be understood by reference to the following description taken in connection with the accompanying drawing in

which Figs. 1, 2, and 3 represent three different embodiments of my invention.

In Fig. 1 there is shown a coaxial cable having a center conductor 1 of uniform cross section and a tubular outer conductor 2 coaxial with conductor 1 and of uniform outside diameter. Insulating disks 3 of any suitable insulating material are provided for maintaining the conductor 1 centrally disposed within the tubular conductor 2. The insulators 3 are centrally perforated to receive the conductor 1 snugly and are of such size as to fit closely within the conductor 2. Moreover, the spacing between the insulators 3 is that required because of mechanical considerations, namely, supporting the conductor 1 within the conductor 2.

It is well known that, when insulating disks such as those shown in Fig. 1 are spaced uniformly within a coaxial cable, reflection of transmitter energy occurs. It has been found, furthermore, that if reflecting points spaced at equal spacings throughout the entire transmission line system are provided with sufficiently short spacings between adjacent points, each point reflecting equal amounts of energy, broad-band transmission of energy is effected. As is well known, this condition occurs when the spacing between adjacent reflecting points is a very small fraction of a wavelength at the highest frequency which it is desired to transmit. The smaller the spacing, the more closely the line approaches a continuous-dielectric line and the wider the band of frequencies which can be transmitted without excessive standing-wave ratio. Accordingly, there is provided in the transmission line of Fig. 1 a plurality of collars or sleeve members 4 formed of any suitable conducting material, such as for example copper. The members 4 may be attached to the inner conductor 1 in any suitable manner similar to that used for the insulators, such as by crimping, or by means of set screws 5.

Fig. 2 illustrates a modification of my improved transmission line in which the reflection points spaced between the insulators 3 comprise collar or sleeve members 6 which are attached to the outer conductor 2 in any suitable manner, such as by crimping or the set screws 7 to reduce the inner diameter of the outer conductor at these points. Moreover, the outer conductor 2 preferably is formed into short sections which are joined together by any suitable means, such as the threaded coupling member 8.

Still another modification of my invention is illustrated in Fig. 3 in which, intermediate the insulators 3, there are employed both the sleeve 4

attached to the inner conductor 1 and the sleeves 6 attached to the outer conductor 2. The sleeves 4 and 6 may be aligned transversely of the transmission line, as shown, or they may be staggered to provide proper reflections.

In the operation of the transmission line disclosed, the sleeve members 4 and 6 serve as capacitive reflection points along the transmission line which are so spaced with respect to the insulators 3, in correlation with the frequency of the energy transmitted over the transmission line, that each sleeve serves to behave like the insulator which it replaces. In the construction of Fig. 3, as well as the other constructions of course, the spacing between the reflective sleeve and the opposite conductor is limited so that the spacing between adjacent conductive surfaces is such that voltage flash-over does not occur.

An important advantage of my improved transmission line is the decrease in power loss over the conventional transmission line employing insulators instead of the reflective members 4 or 6. It has been found that, in a transmission line of the conventional type, when large conductors are used the losses due to the presence of the spaced insulators amount to approximately one-third of the total energy loss of the line. However, by the use of the metal capacitive reflectors 4 or 6, these losses are reduced in proportion to the number of actual insulators used, since the capacitive reflectors 4 or 6 introduce negligible energy loss. Thus, in a line employing my invention as described above, with three out of every four insulators replaced by the sleeves 4, the insulator loss is reduced by 75 per cent and the total losses on the line, by about 25 per cent. Another advantage of my invention is the great reduction in cost of a transmission line for high frequency energy. In lines for transmitting high frequency energy of greater amounts of power, very large outer conductors of the order of three or six inches are required. In such lines, the cost of the insulators forms a large portion of the total cost of the line. Thus, for example, an insulator for a three-inch line costs approximately thirty-five cents, while an insulator for a six-inch line costs in the order of one and one-half dollars. By my improved construction, 75 per cent of the total insulator cost may be eliminated, thus considerably reducing both the initial cost and subsequent operating costs of transmission lines.

While I have shown particular embodiments of my invention, it will of course be understood that I do not wish to be limited thereto since modifications may be made and I aim by the appended claims to cover any such modifications as fall within the true spirit and scope of my invention.

What I claim as new and desire to secure by Letters Patent of the United States is:

1. A coaxial transmission line adapted for operation over a wide band of high frequencies comprising a tubular outer conductor and an inner conductor, a plurality of insulators spaced at regular intervals throughout said line, said insulators providing a plurality of reflection points each causing reflection of the same amount of energy and also causing an undesired energy loss at said frequencies, the spacing between adjacent insulators being adequate for mechanical support of said inner conductor but substantially greater than that which provides sufficiently reflectionless transmission for operation over said wide band, and a plurality of discrete short sections

of said line regularly interspersed with said insulators each providing substantially reduced spacing between said conductors, each of said sections being arranged to provide an additional reflection of the same amount of energy as each insulator but negligible energy loss, the distance between adjacent reflection points throughout said line being short enough to provide sufficiently reflectionless transmission for operation over said wide band.

2. A coaxial transmission line adapted for operation over a wide band of high frequencies comprising a tubular outer conductor and an inner conductor, a plurality of insulators spaced at regular intervals throughout said line, said insulators providing a plurality of reflection points each causing reflection of the same amount of energy and also causing an undesired energy loss at said frequencies, the spacing between adjacent insulators being adequate for mechanical support of said inner conductor but substantially greater than that which provides sufficiently reflectionless transmission for operation over said wide band, and a plurality of short metallic collar members carried by one of said conductors and regularly interspersed with said insulators, said members being arranged to provide additional reflection points each of which causes reflection of the same amount of energy as each of said insulators but with negligible energy loss, the distance between adjacent reflection points throughout said line being short enough to provide sufficiently reflectionless transmission for operation over said wide band.

3. A coaxial transmission line adapted for operation over a wide band of high frequencies comprising a tubular outer conductor and an inner conductor, a plurality of insulators spaced at regular intervals throughout said line, said insulators providing a plurality of reflection points each causing reflection of the same amount of energy and also causing an undesired energy loss at said frequencies, the spacing between adjacent insulators being adequate for mechanical support of said inner conductor but substantially greater than that which provides sufficiently reflectionless transmission for operation over said wide band, and a plurality of short metallic collar members carried by one of said conductors and regularly spaced between each pair of adjacent insulators, said members being arranged to provide a plurality of additional reflection points between adjacent insulators each causing reflection of substantially the same energy as each of said insulators but negligible energy loss, the distance between adjacent reflection points throughout said line being short enough to provide sufficiently reflectionless transmission for operation over said wide band.

4. A coaxial transmission line adapted for operation over a wide band of high frequencies comprising a tubular outer conductor and an inner conductor, a plurality of insulators spaced at regular intervals throughout said line, said insulators providing a plurality of reflection points each causing reflection of the same amount of energy and also causing an undesired energy loss at said frequencies, the spacing between adjacent insulators being adequate for mechanical support of said inner conductor but substantially greater than that which provides sufficiently reflectionless transmission for operation over said wide band, and a plurality of pairs of short metallic collar members regularly interspersed with said insulators, one member of each pair being

carried by said inner conductor and the other by said outer conductor so as to provide substantially reduced spacing between said conductors over a short discrete section of line, said pairs of collar members providing additional reflection points each causing reflection of the same amount of energy as each of said insulators but with negligible energy loss, the distance between adjacent reflection points throughout said line being short enough to provide sufficiently reflectionless **10** transmission for operation over said wide band.

Certificate of Correction

Patent No. 2,473,262.

June 14, 1949.

MARVEL W. SCHELDORF

It is hereby certified that errors appear in the printed specification of the above numbered patent requiring correction as follows:

Column 3, line 31, for "capactitive" read *capacitive*; line 66, for the word "regulator" read *regular*;

and that the said Letters Patent should be read with these corrections therein that the same may conform to the record of the case in the Patent Office.

Signed and sealed this 22nd day of November, A. D. 1949.
